UNITED STATES PATENT OFFICE.

JOHN WEBSTER, OF EAST PROVIDENCE, RHODE ISLAND.

DESIGN FOR A SHAVING-BRUSH.

41,266.

Specification for Design. **Patented Mar. 28, 1911.**

Application filed May 2, 1910. Serial No. 559,042. Term of patent 14 years.

To all whom it may concern:

Be it known that I, JOHN WEBSTER, a citizen of the United States, residing at East Providence, in the county of Providence and State of Rhode Island, have invented a new, original, and ornamental Design for a Shaving-Brush, of which the following is a specification, reference being had to the accompanying drawing, forming part thereof.

The characteristic feature of the design consists in the flatness of the opposite sides of the brush handle, giving it a marked thinness in comparison with its width.

Figure 1 is a side elevation showing the flat side of the brush; and Fig. 2 is an edge view thereof taken at right angles to the plane of Fig. 1.

I claim:

The ornamental design for a shaving brush substantially as shown and described.

JOHN WEBSTER.

Witnesses:

FRANK I. WINSHIP,
F. W. SHANNON.
